WINDOW VENTILATOR

Filed March 5, 1929

UNITED STATES PATENT OFFICE

HARRY P. FISHER, OF SAN FRANCISCO, CALIFORNIA

WINDOW VENTILATOR

Application filed March 5, 1929. Serial No. 344,269.

This invention relates to the type of ventilators that are adapted to be placed in a window opening and the window closed down thereupon, and particularly to a ventilator which is adapted to be permanently attached to the sill of the window so as to be readily swung into or out of the window opening, as may be required.

The object of the present invention is to generally improve and simplify the construction and operation of window ventilators; to provide a ventilator which may be fitted to windows of varying widths; to provide a ventilator which will introduce a maximum of air through a minimum of window space or opening; to provide a ventilator which will prevent entrance of water during windy and rainy weather; and also exclude insects such as flies, mosquitoes etc., and further to provide a ventilator which is adapted to be permanently secured to the sill of the window, so as to be readily swung into or out of the window opening, as required.

The ventilator is shown by way of illustration in the accompanying drawings, in which:

Fig. 1 is a vertical section of a window showing the ventilator installed,

Fig. 2 is a perspective view of the window showing the ventilator installed,

Fig. 3 is a section similar to Fig. 1 but showing the screen extended and the window lowered,

Fig. 4 is a detailed view of the hinge whereby the screen is secured to the hood of the ventilator.

Referring to the drawings in detail, and particularly Figs. 1 and 2, A indicates the lower rail or sash of a window which is adapted to be raised and lowered, B the frame in which the window is mounted, and C the window sill. Secured adjacent opposite ends of the window sill are bearing brackets 2, and pivotally attached thereto are a pair of links, such as indicated at 3.

Attached to the opposite ends of the links is a hood, generally indicated at D. This hood consists of a pair of telescoping plates, such as shown at 6 and 7. These plates are provided with end sections 8. The plates telescope with relation to each other, and as such permit the ventilator as a whole to be fitted to windows of varying widths. The plates are attached to the upper ends of the links 3, as indicated at 9, and the hood or plates may thus be swung to assume the extended position shown in Fig. 3.

Mounted on the inner or lower surface of the hood D is a spring latch 10. Pivotedly secured to the lower surface of the hood by hinges 11, is a screen plate 12. This plate normally assumes the position shown in Fig. 1. In this position the air enters or passes through the screen in the direction of arrow a and it enters the room in the direction of arrow b, the purpose of the screen being mainly that of excluding mosquitoes, flies and other insects. The screen will, of course, retard circulation to some extent and where insects do not bother the screen may be raised to assume the position shown in Fig. 3 and it may there be secured by the spring latch 10. The lower edge of the end plates 8 are provided with inturned ledges or flanges, such as indicated at 8a. These flanges form a support for the free end of the screen 12 when in a lowered position. These flanges also form a support for the ventilator as a whole, so as to prevent marring or cutting of the window sill surface. On windy days the amount of air passing through the screen may be so great as to tend to lift it, thereby permitting a certain amount of insects to enter from time to time, and also produce a rattling or slamming noise. To prevent this, coil springs, such as shown at 14, (see Fig. 4) may be wound about the screen hinges, these springs having sufficient tension to secure the screen in rigid contact with relation to the inturned flanges 8a, thus preventing any rat-

tling or slamming noise, and also preventing entrance of insects.

In view of the fact that the hood D is longitudinally adjustable it is obvious that the 5 screen 12 will be similarly constructed. That is, it will consist of two overlapping screen sections of the usual construction.

In actual operation, the ventilator is permanently attached to the window ledge or 10 sill C by means of the bearing brackets 2. If the window is closed the ventilator will assume the extended position shown in Fig. 3. On the other hand, if the ventilator is to be used it is pulled inwardly or under the window 15 A so that the window may be closed down on top thereon. In this manner it is clamped between the window and the sill and it furthermore provides an opening through which ample ventilation may be obtained. 20 In fact, a maximum of circulation can be obtained through a comparatively small window opening in this manner, as wind currents striking the surface of a building invariably have a tendency to be deflected in 25 an upward direction. The hood D projecting exterior of the surface of the building deflects the upwardly rushing air inwardly through the window opening, thus insuring a more or less forced circulation, the hood 30 also functioning to exclude rain in stormy weather.

The ventilator as a whole is exceedingly simple and substantial in construction, it may be readily installed in any window opening, 35 and as it is longitudinally adjustable, windows of different widths are taken care of. It may also be readily extended or moved into operative position.

While certain features of the present invention are more or less specifically described, 40 I wish it understood that various changes may be resorted to within the scope of the appended claims, similarly, that the materials and finishes of the several parts employed 45 may be such as the manufacturer may decide, or varying conditions or uses may demand.

Having thus described my invention, what 50 I claim and desire to secure by Letters Patent is:

1. The combination with a window frame, its sill, a window vertically slidable in the frame of a hood-shaped ventilator and a link member pivotally connecting the hood to the 55 frame, said link permitting one side of the hood to be swung into the window opening between the sill and the window so as to be secured by the window resting thereon, said hood also adapted to be swung about the 60 link member in an outward direction from the window to permit closing of the window.

2. The combination with a window frame, 65 its sill, a window vertically slidable in the frame of a hood-shaped ventilator, a link

member pivotally connecting the hood to the frame, said link permitting one side of the hood to be swung into the window opening between the sill and the window so as to be secured by the window resting thereon, said 70 hood also adapted to be swung about the link member in an outward direction from the window to permit closing of the window, and a screen member secured to the lower surface of the hood and normally covering 75 the space between the sill and the hood.

3. The combination with a window frame, its sill, a window vertically slidable in the frame of a hood-shaped ventilator, a link member pivotally connecting the hood to the 80 frame, said link member permitting one side of the hood to be swung into the window opening between the sill and the window so as to be secured by the window resting thereon, said 85 hood also adapted to be swung about the link member in an outward direction from the window to permit closing of the window, a screen hingedly attached to the inside of the hood, and means for securing the free side of the screen in a position substantially parallel to the lower surface of the hood.

4. The combination with a window frame, its sill and a window vertically slidable in the frame of a hood-shaped ventilator, end 85 members on said hood engaging the sides of the window frame, and a pair of links pivotally secured at one end to the window sill and at their opposite ends to the lower side of the hood, said links permitting one 100 side of the hood to be swung into the window opening between the sill and window so as to be secured by the window resting thereon, said hood also adapted to be swung about the links in an outward direction away from 105 the window, to permit closing of the window.

5. The combination with a window frame, its sill and a window vertically slidable in the frame of a hood-shaped ventilator, end 110 members on said hood engaging the sides of the window frame, a pair of links pivotally secured at one end to the window sill and at their opposite ends to the lower side of the hood, said links permitting one side of the hood to be swung into the window opening between the sill and window so as to be secured by the window resting thereon, said hood also adapted to be swung about the links in an outward direction away from the 115 window to permit closing of the window, and a screen member secured to the lower surface of the hood and normally covering the space between the sill and the hood.

6. The combination with a window frame, its sill and a window vertically slidable in the frame of a hood-shaped ventilator, end 120 members on said hood engaging the sides of the window frame, a pair of links pivotally secured at one end to the window sill and at their opposite ends to the lower side of 125 the hood.

the hood, said links permitting one side of the hood to be swung into the window opening between the sill and window so as to be secured by the window resting thereon, said
5 hood also adapted to be swung about the links in an outward direction away from the window to permit closing of the window, a screen member secured to the lower surface of the hood and normally covering the space
10 between the sill and the hood, and a latch member for securing the free side of the screen in a position substantially parallel to the lower surface of the hood.
